US00D384731S

United States Patent [19]

Ramacier, Jr. et al.

[11] Patent Number: Des. 384,731

[45] Date of Patent: **Oct. 7, 1997

[54] QUICK CONNECTION COUPLING VALVE ASSEMBLY**[75] Inventors:** Patrick J. Ramacier, Jr., St. Paul; David W. Meyer, Jordan, both of Minn.**[73] Assignee:** Colder Products Company, St. Paul, Minn.**[**] Term:** 14 Years**[21] Appl. No.:** 29,391**[22] Filed:** Oct. 4, 1994**Related U.S. Application Data****[62] Division of Ser. No. 871, Oct. 27, 1992, Pat. No. Des. 357,307.****[51] LOC (6) Cl. .... 23-01****[52] U.S. Cl. ....
